Application June 16, 1947, Serial No. 139,714

Term of patent 14 years

(Cl. D31—4)

To all whom it may concern:

Be it known that we, William T. Blake and Joseph R. Moore, citizens of the United States of America, residing at Handley and Fort Worth, respectively, in the county of Tarrant and State of Texas, have invented a new, original, and ornamental Design for a Swivel, of which the following is a specification, reference being had to the accompanying drawing, forming part thereof.

Figure 1 is a side elevational view of a swivel, embodying our new design shown in locked position.

Figure 2 is an edge elevational view thereof, and

Figure 3 is a perspective view of a swivel embodying our new design shown in open position.

We claim:

The ornamental design for a swivel, substantially as shown.
